[57] **CLAIM**

The ornamental design for a receptacle having dimple surfaces for retaining golf balls, as shown and described.

DESCRIPTION

FIG. 1 is a perspective view of a receptacle having dimple surfaces for retaining golf balls shown in its opened condition, showing my new design;

FIG. 2 is a perspective view of a receptacle having dimple surfaces for retaining golf balls shown in its closed condition, showing my new design;

FIG. 3 is a front elevational view, the rear being identical; FIG. 4 is a side elevational view, the other side being identical; and

FIG. 5 is a top plan view; and,

FIG. 6 is a bottom plan view.
